RESUSCITATOR VALVE TRIGGER

Barry K. Wagner, 313 San Elijo St.,
San Diego, Calif. 92106

Filed July 23, 1973, Ser. No. 381,489

Term of patent 14 years

Int. Cl. D9—01

U.S. Cl. D9—291

FIG. 1 is a perspective view of a resuscitator valve trigger, showing my new design.

FIG. 2 is a bottom plan view thereof.

FIG. 3 is an end elevational view as taken from above FIG. 2.

FIG. 4 is a side elevational thereof, the broken lines are shown for illustrative purposes only.

I claim:

The ornamental design for a resuscitator valve trigger, substantially as shown and described.
